VISUAL SIGNALING DEVICE

Ernst Görler and Henry Fuchs, Berlin, Germany

Application November 18, 1932, Serial No. 643,242
In Germany November 23, 1931

15 Claims. (Cl. 116—52)

Visual signaling devices, such as direction indicators for automobiles etc., are known, in which an intended change in the direction of travel is signaled by an arm which swings out of a casing, such arm being usually illuminated when in its signaling position. The arm is actuated by a Bowden wire, or by an electromagnet. Signaling devices of various kinds are also known in which the signaling arm is caused to continuously swing up and down when in its signaling position.

The object of this invention is to provide such a signaling device in which the signaling arm is operated by (a spring weight or a weight operated cable) or such like means, and is returned into its non-signaling position by the same means of actuation. To this end the actuating member exerts force on the arm on the one side of its axis of rotation, when swinging it out into signaling position, and exerts force on the arm on the other side of its axis of rotation when returning it into its non-signaling position. The device can also be constructed in such a way as to cause the arm to swing continuously up and down, when the arm is in its signaling position.

Another object of the invention is to provide means which operate the actuating member when said means are moving in one direction only. These and other features of the invention will now be more fully described with reference to the accompanying drawing which shows by way of example, one method in which this invention can be carried out and in which:—

Figure 1 shows the signaling arm in its inoperative position, with the cover of the casing removed.

Figure 2 shows the signaling arm in signaling position with the top portion of the casing cover broken away.

Figure 3 shows a front elevation of the signaling arm.

Figure 4 shows a plan view of the inside portion of the right side of the casing in Figure 3 with the operating members in one position.

Figure 5 shows the same view as in Figure 4 but with the operating members in the other position.

The signaling device consists of a casing, having sides 1 and 2, in which, for instance on side 1, is mounted the swinging signaling arm 3 rotating around the pin 4. The signaling arm 3 carries, in known manner, a lamp bulb 5, to which the current is carried through the spring 6 which rests in the non-signaling position upon an insulated knob 7 on a conducting plate, thus cutting the current off from the bulb. The spring 6 is

disengaged from the knob 7 when the signaling arm is raised and connects with the conducting plate.

Upon the signaling arm 3, and supported by bolts 8, is a plate 9 provided with an arcuate slot 10, the axis of which coincides with a pivot 11 on the arm 3 around which pivot turns a movable bearing block 12.

This block 12 carries a pin 13, to which is connected one end of a spring 14, the other end of which spring is connected to a pin 15 attached to the casing. The pin 13 projects through the slot 10 in plate 9. The length of the slot 10 is so selected that in the position of rest of the arm 3, the line of connection of the left hand end of the slot 10 with the pin 15 passes on the left hand side of the pivot of the arm 3, while in the signaling position the line of connection between the right hand end of the slot 10 and the pin 15 passes on the right hand side of the pivot of the arm even when the latter oscillates.

If the pin 13 is brought into the position shown in Figure 2, then the spring 14 pulls the signaling arm into its signaling position, because the pin 13 is then on the right side of the axis of rotation 4 of the signaling arm 3. If the pin is brought back again into the position shown in Figure 1, then the same means of actuation, namely the spring 14 will hold the signaling arm in its non-signaling position.

The switching over of the pin 13 from one side to the other of the axis of rotation of the signaling arm, is effected by a switch-gear shown in Figures 2 and 3. This switch-gear consists of a pivot pin 16 fastened to the casing 2, to which pin is secured a ratchet wheel 17. These teeth are engaged by a pin 18, carried by the switch lever 19, the pin 18 engaging the teeth of wheel 17 under the action of a compression spring 20. The switch-lever or handle 19 may be moved always in clockwise direction by a cable or some such means, which causes pin 18 to turn the wheel 17 and the pin 16. The return of the switch-lever 19 is effected by a spiral spring 21. The switch-lever 19 is secured to a tubular casing 22 and between this tubular casing 22 and the ratchet wheel 17 is another tubular casing 23 which has an elongated slot, the dimension of which limits the amount of movement of the switch-lever 19. There is further a spring 24 between the tubular casing 23 and the wheel 17, one end of which spring is bent upwards so that it is depressed when the ratchet wheel is rotated in a clockwise direction and slides over a tooth. As the lever 19 is returned by the spring 21, the

spring 24 prevents rotation of the wheel 17 and the pin 18 slides over a tooth.

Fixed to the pivot pin 16 of the switch-gearing, and on the inside of the casing 2, is a double armed lever 25 having two pins 26 which may be provided with sleeves for the purpose of reducing friction. If the switch-lever 19, see Figure 5, is moved in the direction of the arrow, the double armed lever 25 is carried with it in the same direction. The right hand pin 26 lifts a plate 27 into the position shown in Figure 4. This causes a pin 28 on the block 12 to be lifted and the block to be rotated around its pivot 11 in such a way, that the pin 13 to which is connected the spring 14, is moved on to the right side of the point of rotation 4 of the signaling arm. (Position in Figure 2.) Actuated by spring 21 the switch lever returns to the position shown in Figure 5.

If the switch-lever 19 is again moved as before, the double arm lever 25 turns another 90°. This, in the first place releases the plate 27, after which the pin 26 comes up against the lower end of a double lever 30 pivoted at 29, and swings this lever in a clockwise direction to cause the upper pressure edge 31 thereof to move the pin 28 to the right, (see Figure 4). The pin 28 is therefore moved in the direction towards the point of the signaling arm (see Figure 2). In other words block 12 revolves round its axis 11 and the pin 13 to which is attached the spring 14 is lifted, whilst the pivot axis 11 makes a circular movement downwards around the pin 4 carrying the signaling arm. This brings the pin 13 to the left side of axis 4 so that the spring 14 pulls the signaling arm 3 back into its non-signaling position within the casing. The plate 27 is returned into the original position shown in Figure 5 by the pressure exerted upon its upper edge by pin 28 which is caused to exert that pressure by spring 14. The pin 28 is positioned on block 12 in such a way that when the signaling arm is in its signaling position as shown in Figure 2, the centre line of the pin 28 coincides with the axis of rotation of the signaling arm on pin 4 so that the signaling arm can be made to swing continuously up and down under the oscillating movement of the spring 14.

What we claim is:—

1. A signaling device comprising in combination a pivoted signaling arm, an actuating member for the arm, means causing successive movements of the actuating member in the same direction to be operative first on one side and then on the other side of the axis of the said arm to swing the arm into and out of signaling position alternately, and means causing an automatic retraction of the said actuating member after each movement thereof.

2. A signaling device comprising in combination with a pivoted signaling arm, a pin slidable in an arcuate slot of the said arm, a spring fixed at one end and secured at the other end to said pin, an actuating member and operating means which on successive movements of the actuating member in the same direction move the pin across the slot to bring the said pin first to one side and then to the other side of the pivot of the signaling arm whereupon the spring raises or lowers the arm through the pin engaging the end of the slot according to the side of the pivot to which the pin has been brought by the said operating mechanism.

3. A signaling device comprising in combination, a pivoted signaling arm, a housing for the arm, a uni-directional actuating member pivoted

externally of the housing below the axis of the signaling arm, means connecting the actuating member with the signaling arm whereby a forward angular movement of the actuating member raises the signaling arm into signaling position and a second forward angular movement of the actuating member draws the said arm out of action within its housing, a spring serving to secure the signaling arm in these respective positions by a pull on that side of the axis of the arm corresponding to signaling position or out-of-action position.

4. A signaling device comprising in combination, a pivoted signaling arm, a plate containing an arcuate slot overhung from the signaling arm, a block pivoted on the said plate adjacent to the axis of rotation of the signaling arm and having a pin riding within the said slot, a spring fixed at one end and connected at its other end to the said pin, an operating pin projecting rearwardly of the said plate, an actuating member and means transmitting the movement of the actuating member to the operating pin, to move said pin along the slot to one side or other of the pivot of the signaling arm, whereupon the spring through the pin engaging with the end of the slot pulls the arm into the raised or lowered position according to which side the first mentioned pin occupies with respect to the axis of rotation of the signaling arm.

5. A signaling device comprising in combination with a pivoted signaling arm, an oscillating block including a member riding in an arcuate slot formed in the signaling arm with its center of curvature coincident with the pivot of said block and moving about the axis of rotation of the arm when the latter is swung, an actuating spring for the arm fixed at one end and means connecting the other end of the spring to the block so as to move the said other end from one side of the axis of rotation of the arm to the other when the block is moved.

6. A signaling device comprising in combination with a pivoted signaling arm, a pivoted block including a member riding in an arcuate slot formed in the signaling arm with its center of curvature coincident with the pivot of said block and moving about the axis of rotation of the arm when the latter is swung, an actuating spring for the arm fixed at one end and connected at the other end to the said member which is moved from one side of the axis of rotation of the arm to the other when the block is moved.

7. A signaling device comprising in combination with a pivoted signaling arm, an oscillating block including a member riding in an arcuate slot formed in the signaling arm with its center of curvature coincident with the pivot of said block and moving about the axis of rotation of the arm when the latter is swung, an actuating spring for the arm fixed at one end, means connecting the other end of the spring to the block so as to move the said other end from one side of the axis of rotation of the arm to the other when the block is moved, switch-over gear movable in one direction only and means operable thereby to move the said block in either direction.

8. A signaling device comprising in combination with a pivoted signaling arm, a block pivoted on the arm and including a member riding in an arcuate slot formed in the signaling arm with its center of curvature coincident with the pivot of said block and moving about the axis of rotation of the arm when the latter is swung, an actuating spring for the arm fixed at one end,

- means connecting the other end of the spring to the block so as to move the said other end from one side of the axis of rotation of the arm to the other when the block is moved, a pin positioned on said block so as to be coincident with the axis of rotation of the arm when in the signaling position, and means operating on said pin for moving the block about its pivot to swing the signaling arm.
9. A signaling device comprising in combination with a pivoted signaling arm, an oscillating block pivoted on the arm and including a member riding in an arcuate slot formed in the signaling arm with its center of curvature coincident with the pivot of said block and moving about the axis of rotation of the arm when the latter is swung, an actuating spring for the arm fixed at one end, means connecting the other end of the spring to the block so as to move the said other end from one side of the axis of rotation of the arm to the other when the block is moved, a pin positioned on said block so as to be coincident with the axis of rotation of the arm when the latter is in signaling position, and switch-over gear movable in one direction only and means actuated thereby to act on said pin to move said block in either direction.
10. In combination with a signaling device according to claim 5, switch-over gear for oscillating said block, comprising a pivot pin, a toothed wheel fixed to the pivot pin, a one-way operating pawl acting on the toothed wheel, a spring returning the pawl idly over the toothed wheel when the pawl is released, a double armed lever fixed to said pivot pin, and means connecting said lever with said block so that as the said lever is moved on each operating stroke of the pawl, the block is moved to swing the signaling arm.
11. A signaling device comprising in combination with a pivoted signaling arm, an oscillating block pivoted on the arm and including a member riding in an arcuate slot formed in the signaling arm with its center of curvature coincident with the pivot of said block and moving about the axis of rotation of the arm when the latter is swung, an actuating spring for the arm fixed at one end, means connecting the other end of the spring to the block so as to move the said other end from one side of the axis of rotation of the arm to the other when the block is moved, a pivot pin, a toothed wheel fixed to the pivot pin, a one-way operating pawl acting on the toothed wheel, a spring returning the pawl idly over the toothed wheel when the pawl is released, a double armed lever fixed to the said pivot pin, a pin positioned on said block so as to be coincident with the axis of rotation of the signaling arm when in the signaling position, and means connecting said lever with said pin so that as the said lever is moved on each operating stroke of the pawl, the block is moved to swing the signaling arm.
12. A signaling device comprising in combination with a pivoted signaling arm, an oscillating block including a member riding in an arcuate slot formed in the signaling arm with its center of curvature coincident with the pivot of said block and moving about the axis of rotation of the arm when the latter is swung, an actuating spring for the arm fixed at one end, means connecting the other end of the spring to the block so as to move the said other end from one side
- of the axis of rotation of the arm to the other when the block is moved, a pivot pin, a toothed wheel fixed to the pivot pin, a one-way operating pawl acting on the toothed wheel, a spring returning the pawl idly over the toothed wheel when the pawl is released, a double armed lever fixed to said pivot pin, means connecting said lever with said block so that as the said lever is moved on each operating stroke of the pawl the block is moved to swing the signaling arm.
13. In combination with a signaling device according to claim 5, switch-over gear for oscillating said block comprising a pivot pin, a toothed wheel fixed to the pivot pin, a one-way operating pawl acting on the toothed wheel, a spring returning the pawl idly over the toothed wheel when the pawl is released, a double armed lever fixed to said pivot pin, a pin on said block, a pivoted lever having one end in the path of the arms of said double armed lever, and the other end in the path of said pin, a plate pivoted on said pivoted lever, said plate engaging said pin and lying in the path of the arms of said double armed lever, whereby as the latter is moved on each operating stroke of the pawl the block is moved to swing the signaling arm.
14. A signaling device comprising in combination with a pivoted signaling arm, an oscillating block pivoted on the arm and including a member riding in an arcuate slot formed in the signaling arm with its center of curvature coincident with the pivot of said block and moving about the axis of rotation of the arm when the latter is swung, an actuating spring for the arm fixed at one end, means connecting the other end of the spring to the block so as to move the said other end from one side of the axis of rotation of the arm to the other when the block is moved, a pivot pin, a toothed wheel fixed to the pivot pin, a one-way operating pawl acting on the toothed wheel, a spring returning the pawl idly over the toothed wheel when the pawl is released, a double armed lever fixed to said pivot pin, a pin positioned on said block so as to be coincident with the axis of rotation of the arm when in the signaling position, a pivoted lever having one end in the path of the arms of said double armed lever and the other end in the path of said pin, a plate pivoted on said pivoted lever, said plate engaging said pin and lying in the path of the arms of said double armed lever, whereby as the latter is moved on each operating stroke of the pawl, the block is moved to swing the signaling arm.
15. The combination with the device according to claim 14, of a tubular casing surrounding the toothed wheel, a handle to said pawl secured to said casing, a second tubular casing fixed within the first mentioned casing and having a slot through which the pawl projects, said slot limiting the movement of the handle, and a spring engaging between the toothed wheel and the second mentioned casing so that its inwardly bent end slides over a tooth and prevents contra-rotation upon return of the handle.
